FRANK A. MILLER, OF OAKLAND, CALIFORNIA, ASSIGNOR TO SAN FRANCISCO-SACRAMENTO RAILROAD CO., OF OAKLAND, CALIFORNIA, A CORPORATION OF CALIFORNIA.

SIGNALING SYSTEM.

Application filed June 11, 1923. Serial No. 644,633.

This invention relates to a scheme where-
by an event, such as the arrival of a vehicle
or train at any of a plurality of selected
points, causes the transmission of a signal to
5 a central location, such as a train dispatcher's
office.

The desirability of transmitting such sig-
nals in a reliable and simple manner is evi-
dence. It is thus one of the objects of my
10 invention to provide a novel system of sig-
naling whereby these desirable results may
be readily accomplished.

In such systems it is advantageous to as-
sociate a certain signal with the signaling
15 points, which is peculiar to it, so that the
receipt of the signal at the dispatcher's of-
fice will show that a train has passed a par-
ticular point. It is one of the objects of my
20 invention not only to transmit this intelli-
gence, but also the direction in which the
train is proceeding.

I accomplish these functions by the aid of
relatively simple electric circuits. All of
the transmitting arrangements connect to a
25 common circuit, so that variations in the
current flow in this circuit in a predeter-
mined sequence, will affect a receiver such
as a tape recorder, in the dispatcher's office.
All of the signals, no matter from what
30 point, affect this common receiving device
and its operating circuit. Under such cir-
cumstances, there is a possibility that more
than one train at any time will cause the
actuation of the recorder, and interference
35 and confusion would result. An important
advantage of the use of my system is that
such interference is obviated, and that the
signals must come in succession, if necessary
by delaying some of them temporarily.
40 However, none of the signals are ever sup-
pressed; they may be merely delayed by the
proper time interval to permit other signals
which were earlier started, to be completed.
These results I obtain by various interlocked
45 circuits, which ensure that the signals will
be transmitted in succession, and not simul-
taneously.

My invention possesses other advan-
tageous features, some of which with the fore-
going, will be set forth at length in the fol-
lowing description, where I shall outline in
full that form of the invention which I
have selected for illustration in the draw-
ings accompanying and forming part of the

present specification. Although I have 55
shown in the drawings but one embodiment
of my invention, I do not desire to be lim-
ited thereto, since the invention as expressed
in the claims may be embodied in other
50 forms also.

Referring to the drawings:

Figure 1 is a wiring diagram of one por-
tion of a system embodying my invention,
in which is indicated the circuit connections
between the train dispatcher's office or re-
ceiving point, and an intermediate signaling
55 station;

Fig. 2 is a wiring diagram of that portion
of the system which includes the signaling
station farthest from the train dispatcher's 70
office or receiving point;

Fig. 3 is a side elevation of one form of a
motor driven code wheel and its appurte-
nances, as they may be utilized at interme-
diate stations; and

Fig. 4 is an end view of the device shown
in Fig. 3.

At the signal receiving station, there may
be a local receiving circuit, including a
source of electrical energy 11, telegraph re-
lay contacts 12, and a signal recording or
receiving device 13, preferably a time clock
80 printer. This circuit is arranged to be en-
ergized upon making of the relay contacts
12. The relay 14, for performing this func-
tion, is operated in response to the trans-
mission of coded signals by a train passing
85 a distant point. The circuit arrangement
for performing this function will now be
described.

In the present instance the relay 14 is ar-
ranged to be operated by direct current
from a battery 15 having its negative pole
grounded as at 16. The connection 17 leads
to a telephone system, and in this way the
90 direct current signaling impulses may use
the same wires for one side of the signal
circuit, as for telephoning. Such telephone
systems form a part of the regular equip-
ment for the train dispatcher, and there is no
95 necessity for supplying additional wires for
the signals. The other side of the signaling
circuit may be completed through ground
and the grounded connection 16. In order
that the telephone wires may be used for the
100 signal currents in an efficient manner, the
telephone system is split up into inductively
coupled sections, one such section being in-

dicated by the wires 21 and 22, and the coils 19, 20, 23, and 24. The coupling is effected from one section to another by the aid of these coils. Furthermore the points where the sections are coupled are chosen at locations near to the signaling stations, so that the wire 17, for example from the receiving relay 14, may be readily connected to a point 18 central between the two coupling coils 19 and 20. It is thus evident that the telephone wires 21 and 22 form two paths in parallel for the signaling current between the relay 14 and a point 25 midway between the two coupling coils 23 and 24.

15 The splitting up of the telephone wires into sections of this sort does not in any way hinder the use of the telephone system, since the adjacent sections are all inductively coupled together. Thus the coils 19, 20 at 20 the right hand end of the section under consideration are coupled to coils 26, 27 of the next section to the right of the dispatcher's station. Similarly at the left hand end of the section, coils 23 and 24 are coupled to the coils 28 and 29 of the next section to the left. Such an arrangement may be obviously multiplied as needed, in order to provide as many tapping in points such as 18, 25, and 30 as desired for the proper interconnection 25 of all the points when the passage of trains causes the transmission of a direct current signal to the dispatcher's station.

In Fig. 1, I illustrate the circuit arrangement at a signaling station 31 which is nearest the dispatcher's station. For this reason there is but one section of the telephone lines included between these two stations, but of course the same scheme of connections may be used for stations even farther removed, as will become evident from the description. The connection between the telephone sections includes wires 32 and 33, as well as a circuit controlling element, such as a relay 34. The equivalent of these connections exist at all stations, except that farthest from the dispatcher's office. In this way, the telephone sections form a connected series of wires between the signaling stations. Due to the fact that the tapping in points, such as 30, 25 and 18 are neutral as regards the telephone system, no alternating current disturbance can result from utilizing these points.

In order to transmit a signal from station 31 to the receiving device 13, I prefer to utilize a code wheel 35, which when rotated causes electrical contact to be made between the contacts 36, 37, and 40 in a predetermined order, depending upon the number and arrangement of the projections 38 on the code wheel 35. One of the contacts, such as 36, is connected to ground at 39, while the other two, 37 and 40, connect respectively to wires 32 and 33. The code wheel 35 is so arranged 60 that its first movement serves to connect contacts

37 and 40 and thereby short circuit relay 34, which controls the operation of the device to prevent it from being interfered with from other stations, once the code wheel is set into operation. The description of 70 this feature of the invention will be described hereinafter. For the present it is sufficient to note that further movement of the code wheel 35 serves to bring one of the projections 38 around to connect ground 39 to the 75 telephone wire tap 25, by the aid of contact 36, and that contact is maintained between contacts 37 and 40 (which serve to shunt out the relay 34) throughout the entire active movement of the code wheel 35. 80

The complete signaling circuit when contact 36 is active, may now be traced. Starting at the right hand terminal of source 15 in the train dispatcher's office, the signaling current flows through grounded connection 16, through ground, to the station 31 where it flows through grounded connection 39, contacts 36 and 40, connection 33, point 25, where the circuit divides—one branch including coil 23, wire 22, and coil 19, the other including coil 24, wire 21 and coil 20; at point 18 the circuit reunites, and thence continues through connection 17, relay 14, and to the left hand terminal of battery 15. The relay 14 in turn closes the circuit for 95 the recorder 13.

For each of the other stations also, a similar set of connections is completed when sending signals, the sole difference being that more than one inductively coupled telephone section is traversed by the signaling current, and that the current also flows through relays such as 34 which are interposed between the sections. All of these interposed relays, corresponding to all of the 100 intervening stations, are energized and perform a controlling function, as has been intimated hereinbefore, the description of which it is inexpedient to set forth at this time. 110

In order to transmit the signals, it is necessary to rotate the code wheel 35, and for accomplishing this result, I show a small electric motor 41, having a field winding 42 energized from any appropriate source. It is of course possible to utilize other forms of motive power. This motor is rendered active automatically in response to the passage of a train past the station, and a signal may thereby be transmitted. The control of the motor circuit may be effected by any appropriate device which is operated by the train; in the present instance I show a pair of normally closed switches 43 and 44, located near each other along the track and operated by the passage of a train. Such switches are usually inclosed in what are termed track boxes, and are well-known in the art of railway signaling. Two such switches are indicated, in order to provide 125 130

directional signaling; that is, a train coming from right to left will operate switch 43 first, while one on the opposite direction will operate switch 44 first, and different signals may be produced by such an arrangement. I shall now describe how a train coming from right to left produces a signal, and shall afterward describe how a different signal may be sent when the train is traveling in the opposite direction.

In order to secure these effects, I control motor 41 by the track switches 43 and 44 in such a way that the code wheel 35 is driven in one direction when the train comes from the right, and in the opposite direction when the train comes from the left. The energizing source for motor 41 is in the present instance a battery 45, which also serves as a local source for the local control circuits. When a train, coming from the right, operates to open switch 43, the immediate consequence is a deenergization of a normally energized relay 46. The circuit for this relay when energized may be traced as follows: from the positive terminal of battery 45, connection 47, switch 43, relay 46, and connections 48, 49, and 50 back to the negative terminal of battery 45. Contacts 51, which are normally out of engagement, close when this relay 46 becomes deenergized in response to the opening of the switch 43. These contacts in turn cause the energization of one of the main control relays 52, the circuit for which may now be traced as follows: from the positive terminal of battery 45, connection 47, contacts 51, connections 53 and 54, relay 52, and connection 55 back to the negative side of the battery 45.

After the contacts 51 are completed, in the manner described, the relay 52 remains energized until after the signal is sent, even if the relay 46 picks up its contact 51 in response to the clearing of the train past the switch 43. This result is accomplished by the aid of a holding circuit for relay 52, including the contacts 56 which are closed when relay 52 is energized. The holding circuit may be traced as follows: from the positive terminal of battery 45, connection 57, contacts 56, connection 58, a pair of spring contacts 59, connection 54, relay 52, connection 55, back to the negative terminal of battery 45. The relay circuit thus stays closed until the spring contacts 59 separate, and this is accomplished only after the code wheel 35 completes its movement. This result is obtained by providing a mechanical connection between these contacts 59 and the code wheel 35, in a manner that will be described at length hereinafter.

The relay 52 may control a plurality of other sets of normally open contacts. Thus contacts 61 are in a circuit including a clutch magnet 62. This clutch, when energized serves to disconnect the motor 41 from the

code wheel 35, so that it is then incapable of transmitting a signal. The clutch is provided for the very important function of preventing two stations from transmitting signals at the same time, and the arrangement is therefore such that while one station code wheel 35 is actuated, the clutches for other stations that may be attempting to signal are inactive, and remain so until the line clears. How this is accomplished will 70 become evident from a tracing of the clutch magnet circuit, which is as follows: from the positive terminal of battery 45, connection 57, contacts 61, contacts 63 of relay 34, connection 64, clutch magnet 62, and connections 49 and 50, back to the negative terminal of battery 45. It is to be noted that this circuit is completed only when relays 52 and 34 are energized; and this condition corresponds to an attempt by the local 80 station to transmit a signal (causing relay 52 to be energized) and to a transmission of a signal from another station (causing relay 34 to be energized). If the signals from the distant station are started sooner 85 than the code wheel 35 at this station, then it is evident that relay 34, in picking up and making contacts 63, will place the clutch magnet circuit in proper condition to be completed as soon as switch 43 opens and 90 relay 52 is energized. If however no distant station is sending a signal, then the clutch remains in its operative position, even after contacts 61 of relay 52 close. By 95 providing these contacts 61 operated by relay 52, it is assured that current through the clutch coil 62 may flow only upon an interference between stations, and not every time that a distant signal is being transmitted. A corresponding saving in current 100 is thus obtained. It is to be noted that relay 34 is arranged to have a retarded opening after deenergization, so that it may maintain the contacts 63 closed during the whole period of signaling by the distant 105 station.

Relay contacts 65 and 66 serve to complete the circuit for motor 41, and if clutch magnet 62 is deenergized, the code wheel 35 will be driven around once to transmit a signal. 115 The motor circuit may be traced as follows: from the positive terminal of battery 45, connection 57, contacts 65, connections 67 and 68, motor 41, connections 69 and 70, contacts 66 and connection 50 to the negative side of battery 45. It is to be noted that the lower terminal 71 of the motor is connected to the positive side of the battery 45, while the upper terminal 72 is connected to the negative side. Let us assume that for this 120 connection, the motor 41 will rotate in a direction causing the code wheel 35 to rotate in a clockwise direction. Under such circumstances the wheel will transmit the signal 21 due to the spacing of the projections 125 130

38 in this instance, which signal will be properly recorded as described hereinbefore at the dispatcher's office. As soon as wheel 35 makes one revolution, it operates to open contacts 59 momentarily, and relay 52 is restored to its normal open position. The motor circuit will then be interrupted at the contacts of this relay and the apparatus will return to the position shown in the figure.

10 It is to be noted that upon passage of a train as described, the relay 52 is under all circumstances energized, and motor 41 is operated, even if the clutch is inactive due to signaling commenced at a distant station; 15 and that this motor stays energized until contacts 59 open. There is thus an assurance that as soon as the distant station is through signaling, causing deenergization of relay 34, the motor 41 will be active until the code wheel 35 makes the required angular movement. There is no danger of any signal being lost, due to this arrangement, the inactive condition being restored only after the signal is sent.

20 In case a train proceeds from left to right, causing switch 44 to be first operated, the arrangement is such that the motor 41 rotates in a reverse direction, and code wheel 35 is caused to send a reversed message, such as 12, instead of 21 as in the first instance. The operation of the system to secure these effects is similar to that already described. A relay 73 is deenergized as soon as switch 44 opens. The circuit for this relay and the 25 switch 44 is in parallel to that of the relay 46 and switch 43, and need not be further described. It is to be noted however, that these two relays are interlocked, so that if one operates, the other cannot. In this way 30 that relay alone is active which is first operated. The relay contacts 75 close as the relay 73 is deenergized, and serve to complete the circuit for the other control relay 76 through the following path: from the 35 positive terminal of battery 45, connection 47, contacts 75, connection 77, relay 76, to the negative terminal of battery 45. As soon as relay 76 picks up, a holding circuit 40 is closed for it, which may be traced as follows: from the positive terminal of battery 45, connection 57, contacts 78, connection 79, a pair of spring contacts 80 operated to open 45 only after the code wheel has completed its signaling movement, connections 81, 71, relay 76, back to the negative terminal of battery 45.

50 Contacts 81 operate entirely similarly to contacts 61; to complete the clutch magnet circuit in case relay 34 is energized in response to the transmission of a signal from a distant station.

55 Contacts 82 and 83 control the motor 41, the circuit of which may be traced as follows: from the positive terminal of battery 45, connection 57, contacts 82, connections

84 and 69, motor 41, connection 68, contacts 83 and connection 50 back to the negative terminal of battery 45. In this instance, the upper terminal 72 of the motor is connected to the positive side of the battery, while the lower terminal is connected to the negative side. The motor therefore, runs in a direction opposite to that if relay 52 be energized, and the code wheel is also reversed, and transmits a reversed signal to indicate 75 that the train passed in a reverse direction.

80 Due to the fact that relays 46 and 73 are interlocked as indicated, only one of the relays 52 and 76 may be energized. In this way it is certain that there can be no signaling interference, because the first of the two relays 73 and 46 to drop prevents the other from dropping. Furthermore, due to the provision of contacts 37 and 40 which short circuit relay 34 whenever code wheel 35 has 85 moved far enough to bring the lower portion of the signaling segment 85 under contact spring 37, it is assured that no distant signaling station can operate the relay 34 and cause the clutch magnet 62 to be energized to disconnect the motor.

90 The transmission of a signaling current from any intermediate station such as 31 causes the energization of all other relays 95 equivalent to relay 34 that are located between the intermediate station and the dispatcher's office, and thus prevents them from sending a signal until the station 31 has completed its signal. It is however, necessary to provide for the energization of all 100 relays such as 34 for all the stations, even those farther removed from the dispatcher's office than the sending station. It is for this reason, mainly, that a slightly different system is provided at the end station 86, 105 which is illustrated in Fig. 2. At this station there is a battery 87 grounded at its negative terminal as shown at 88, so as to oppose the similarly grounded battery 15 at the dispatcher's office. The positive terminal is connected to a relay 89 which is the equivalent of relay 34 at the intermediate stations. This relay is connected to the telephone system at point 90 through a connection 91, normally closed contacts 92 and 110 93, and connection 94. Thus when any intermediate station such as 31 is signaling, a current flow is set up from its ground connection 39, not only to the dispatcher's office ground 16, but also to the ground 88 at the 115 end station, thence through battery 87, relay 89 and through the telephone system back to the intermediate stations through all the intervening relays 34 of those stations included between the end station 86 and the 120 signaling intermediate station 31. Thus all 125 of the clutch magnets are energized for all other stations.

125 When end station 86 is to transmit a signal by rotating its code wheel 95, the first 130

operation performed by this wheel is the opening of the contact between springs 92 and 93, whereby the circuit for relay 89 is opened, and it is assured that the motor 41 clutch will not be rendered inactive. Continued rotation of wheel 95 will serve to connect contact 92 with contact 96, whenever a projection 97 passes under the contact 92. The contacts 92 and 96 complete the signaling circuit, from ground 88, through these contacts and lead 91 to point 90. The operation and connection of all other devices, such as relays 52 and 76, and the motor 41, are substantially identical with the devices described in connection with the intermediate station 31, and therefore require no further explanation.

From the foregoing it is evident that proper sequence of the signaling from the various stations is assured. The motors 41, once the appropriate relay 52 or 76 is energized, remain active until they serve to send in their signal by aid of the code wheels. Furthermore, although a system utilizing only direct current has been described, it is evident that other kinds of current could in part or in whole be used. Furthermore, many of the relay circuits may be varied without substantial variation in ultimate function of the system.

There remains to be described a form of the device that may be used to provide the proper mechanical connections between the motor, code wheel, clutch, and contacts associated therewith. Such an arrangement is illustrated in Figs. 3 and 4, wherein I show a base 98, which in conjunction with a cover 99, serves to house all the parts in a neat manner. The motor 41 is secured to the base, and through a train of reduction gearing 100, is operatively connected to a shaft 101. This shaft is journaled in the standards 102. The code wheel 35 which is fastened to one face of a collar 103, is loosely mounted on this shaft.

The clutch magnet 62 is supported on the base 98, as by the standard 108, and in its deenergized condition as shown it permits the shaft 101 to drive the code wheel 35. For this purpose a collar 104 is splined in shaft 101, and is urged toward the wheel 35 by the compression spring 105. This collar has an extending pin 106 which is arranged to coact with a projection such as pin 107 on the code wheel 35, so that in the position shown the code wheel may be rotated by the rotating collar 104. The magnet 62 however has a forked armature 109 which when attracted, pulls the collar 104 away from the wheel 35 and against the force of spring 105. The armature is pivoted on edges 110 of the member 111 forming a part of the magnetic circuit for the clutch magnet 62. In order to keep the armature 109 in proper position, with re-

spect to this member 111, it is provided with slots 112 fitting over projections 113 on the member. Furthermore a spring 114 appropriately supported, is used to urge the armature 109 away from the electromagnet 62. In the present instance the spring 114 acts on a short extension of the armature, through which passes the spring post 115 fastened to a turned-up lip 116 of the member 111.

It is evident from the foregoing that energization of magnet 62 effects an immediate uncoupling of the code wheel 35 from the shaft 101, so that it will be prevented from transmitting its signal. The contacts controlled by the wheel as it rotates are also shown, and in the present instance are arranged to be used at an intermediate station 31, although minor changes may readily be made to adapt the device for use at the end station 86. The contact member 37 has a cam follower 117 which is in the path of the code wheel segment 35 and projections 38, and is fastened to base 98 as by aid of the insulating block 118. As soon as the segment 35 passes under this follower, and even before projections 38 pass thereunder, the contact member 37 is flexed sufficiently to engage the contact member 40, and a further flexing, due to the passage of the projections 38 under the follower 117, serves to connect it to the contact member 36. The contact on member 37 is wide enough to bridge both members 36 and 40, as clearly shown in Fig. 4. The contact members 40 and 36 are also appropriately attached to the other side of block 118, and may be adjusted so as to be properly spaced from the member 37, by the aid of adjusting screws 119. These screws engage the members 36 and 40, and are threaded in upright standards 121 which may also be attached to the block 118. The operation of these contacts in the system has been described in detail, and it is considered not essential to set it forth at this point.

Both sets of contacts 59 and 80 are arranged to be operated to close as soon as the code wheel 35 moves from its inactive position. This is accomplished by the aid of the cam follower 122 which slips in a shallow depression 123 of collar 103, and is urged into this position by the spring 124 fastened to an insulation block 125. This follower serves also, by friction, to maintain the wheel 35 in its inactive position if clutch magnet 62 becomes energized due to the transmission of a signal from a distant station and the closing of contacts 63 of relay 34. Furthermore, this follower carries a plurality of contact pieces 126 and 127 which form one of the elements of the sets 59 and 80, the other cooperating elements being formed by the spring members 128 and 129. These members may likewise be attached to the block 125. In order to adjust the relative positions of these members 128 and 129, stand-

ards 130 may be used in which are threaded the adjusting screws 131. It is evident that the code wheel 35 must make a complete revolution before the contacts 59 and 80 are permitted to open, since the follower 123 will only then be permitted to reenter the depression 123.

In order to provide a neat scheme of connections for the motor 41 and for the various contacts, a plurality of binding posts 132 may be included in the box formed by the base 98 and cover 99.

A brief review of the operation of the system may now be set forth. Assuming that 15 a train or other vehicle passes station 31 from right to left, the switch 43 will be opened. This causes relay 46 to drop its armature, making contacts 51. At the same 20 time, relay 73 is held from dropping its armature by an interlock, so as to prevent interference when the train reaches switch 44. The contacts 51 complete the circuit for control relay 52. The motor 41 is energized immediately, since its circuit is completed by contacts 65 and 66 of this relay. In case no distant station is active, relay 34 is deenergized, and the motor remains clutched to the code wheel 35, the clutch being in the position of Fig. 4. After the 25 code wheel 35 rotates through a very small angle, contacts 59 are completed and serve to shunt the contacts 51, so that even after the train passes the switch 43, a holding circuit for control relay 52 through these contacts 30 will be completed, which may be broken only after the wheel 35 makes a complete revolution, and has transmitted its signal. At that time, the contacts 59 open, relay 52 is open-circuited, and motor 41 is deener- 35 gized.

In case relay 34 is however energized due to the transmission of a signal from a distant station, the clutch magnet 62 is energized when relay 52 picks up, through both 40 sets of contacts 61 and 63. The contacts and the clutch itself are so arranged however, that the clutch does not immediately respond, but permits rotation of wheel 35 far enough to operate contacts 59. This may 45 be secured for example, by delaying the closure of contacts 61, in any well-known manner, or by any other well-known means, as by the clutch arrangement itself. In this way it is certain that a holding circuit for 50 relay 52 will at any rate be completed, so as to keep motor 41 rotating. When the distant signaling is completed, relay 34 drops, deenergizing clutch magnet 62, and causing the motor to rotate the code wheel 55 as before.

As soon as the code wheel 35 rotates far enough to complete the contacts 37 and 40, and even before the transmission of a signal, the relay 34 will be short-circuited, so that 60 signals attempted to be sent from a distant

station after that time will have no effect on the circuit for the clutch magnet 62. When two signals from two separate stations are attempted to be sent substantially simultaneously, that one will be sent first which first causes the making of contact between 37 and 40. Later on, when contact with member 36 is also established, the clutch for the interfering station is temporarily inactive, due to the energization at that station of a relay 75 which is the equivalent of relay 34. It is thus seen that proper sequence of the signals must be observed when my system is used, and confusion is satisfactorily obviated.

I claim:

1. In a railroad signaling system, a plurality of remote automatic transmitters, a common receiver associated with said transmitters, each transmitter being adapted to be operated to effect either one of two characteristic responses at the receiver, means associated with a railroad track section adjacent a corresponding transmitter to initiate operation of such transmitter to produce one characteristic response when a train passes in one direction and another characteristic response when a train passes in another direction and means for delaying the operation of a subsequently initiated transmitter until termination of the signal from said first initiated transmitter.

2. In a railway signaling system, a plurality of transmitters located respectively near remote sections of track, a circuit over which the transmitters may send a signal by varying the current flow therein, said transmitters being arranged in parallel relation with respect to the circuit, means associated with each transmitter responsive to the passing of a train over its respective section to 105 actuate it, each of said means being constantly capable of operation, whereby substantially simultaneous operation of said means can result, and means responsive to the transmission of a signal by one of the 110 transmitters, for delaying the transmission of signals from any of the other transmitters.

3. In a signaling system, a plurality of transmitters, said transmitters being arranged in parallel relation and adapted to signal over a common medium, movable means for operating each transmitter, and means associated with each transmitter for delaying the operation of the transmitter 115 while maintaining the operating means in motion, until after the medium is clear.

4. In a signaling system, a plurality of transmitters, a circuit over which the transmitters may send a signal by varying the 120 current flow therein, sources of motion, one for each transmitter to cause it to transmit a signal, said source of motion being rendered active in response to the occurrence of 125 an event associated with that transmitter,

and means for disconnecting the source from the transmitter in response to current conditions in the circuit, while maintaining said source active, whereby the signal may be delayed.

5. In a signaling system, a plurality of transmitters, a circuit over which the transmitters may send a signal by varying the current flow therein, sources of motion, one for each transmitter to cause it to transmit a signal, said source of motion being rendered active in response to the occurrence of an event associated with that transmitter, and means for disconnecting the source from the transmitter while maintaining said source active and until after the circuit is clear of signals transmitted by other transmitters.

6. In a signaling system, a plurality of transmitters, a circuit over which the transmitters may send a signal by varying the current flow therein, sources of motion, one for each transmitter to cause it to transmit a signal, said source of motion being rendered active in response to the occurrence of an event associated with that transmitter, means for maintaining this source of motion active until the signal is transmitted, and means for disconnecting the source from the transmitter while maintaining said source active in response to current conditions in the circuit, whereby the signal may be delayed.

7. In a signaling system, a plurality of transmitters, a circuit over which the transmitters may send a signal by varying the current flow therein, sources of motion, one for each transmitter to cause it to transmit a signal, said source of motion being rendered active in response to the occurrence of an event associated with that transmitter, means for maintaining this source of motion active until the signal is transmitted, and means for disconnecting the source from the transmitter while maintaining said source active, and until after the circuit is clear of signals.

8. In a signaling system having a plurality of transmitters with motors driving them, automatically and separately actuated in response to the occurrence of an event associated with each transmitter, and adapted to transmit signals over a common medium, the method of insuring that the signals will not interfere, which comprises actuating any of the motors when the associated event occurs, maintaining said motors active, connecting that motor which is the first to start to its transmitter, disconnecting all of the other motors, connecting them in succession after the first transmitter has completed its transmitting function, and stopping all of the motors after they have caused their respective transmitters to function.

9. In a railway signaling system, a circuit, more than two transmitters adapted to be connected in parallel to the circuit at different points thereof and located respectively near remote track sections, a receiver located near one end of the circuit for receiving all of the signals from the transmitters, and means associated with each transmitter operated independently of the receiver and responsive to the actuation of any one of the distant transmitters, for disabling the transmitter until a distant transmitter completes its signal.

10. In a railway signaling system, a circuit, more than two transmitters adapted to be connected in parallel to the circuit at different points thereof and located respectively near remote track sections, said transmitters being adapted to transmit signals automatically in response to the passage of a train over a respective track section, a receiver located near one end of the circuit for receiving all of the signals from the transmitters, and means associated with each transmitter operated independently of the receiver and responsive to the actuation of any one of the distant transmitters for delaying the actuation of the transmitter until the distant transmitter completes its signal.

11. In a signaling system, a circuit, a plurality of transmitters adapted to be connected in parallel to the circuit at different points thereof, and to transmit signals automatically and separately in response to the occurrence of an event associated with the transmitter, means whereby any transmitter located between the receiver and the farthest transmitter may vary the current flow in that portion of the circuit located between it and the receiver and thereby transmit a signal, means responsive to the variations in current flow for disabling the transmitters located between the transmitting station and the receiver until the transmitter completes its signal, means for completing a circuit between the transmitter and the farthest transmitter for likewise disabling all the transmitters located farther from the receiver.

12. In a signaling system, a circuit, a receiver near one end of the circuit, a plurality of transmitters adapted to vary the current flow to the receiver through the circuit, and connected in parallel at different points along the circuit, and means whereby the transmission of a signal from any intermediate transmitter will cause the signals attempted to be sent from any of the other transmitters, to be delayed, comprising electroresponsive elements included in the circuit, one for each transmitter, affected by variations in current in the circuit, and means for energizing that part of the circuit included between the intermediate transmitter and the end transmitter in ac-

cordance with the signals sent from the intermediate transmitter to the receiver, whereby all other transmitters may be affected to delay their signals.

13. In a signaling system, a circuit a plurality of transmitters associated with the circuit at different points thereof, electro-responsive devices in the circuit, one for each transmitter, motors for operating the transmitters, means for causing any one of said motors to move in response to the occurrence of an event associated with that transmitter which is operated by said motor, means operated by the electroresponsive device associated with said transmitter for disconnecting the motor from the transmitter for the period in which signals are transmitted from other stations, and means for maintaining the motor in motion until the transmitter is actuated to complete its signal.

14. In a signaling system, a circuit, a plurality of transmitters associated with the circuit at different points thereof, electro-responsive devices in the circuit, one for each transmitter, motors for operating the transmitters, means for energizing any one of said motors in response to the occurrence of an event associated with that transmitter which is operated by said motor, means for disconnecting the motor from the transmitter, controlled by the electroresponsive device associated with said transmitter for the period in which signals are transmitted from other stations, and means disabling the electroresponsive device in response to a small initial movement of the transmitter, whereby it is assured that the signal can be completed without interference from the electroresponsive device.

15. In a signaling system, a transmitter adapted when operated to transmit a coded signal, a motor for operating the transmitter, means for causing the motor to move in response to an event, a clutch between the motor and the transmitter, means for disconnecting the clutch in response to the existence of a signaling condition in the circuit before the transmitter is active to send a signal, and means maintaining the motor in motion until the transmitter has been actuated to send its signal.

16. In a system for transmitting a signal whenever a train passes a given point, a code wheel, means for rotating the wheel in opposite directions in response to opposite directions of travel of passing trains.

17. In a system for transmitting a signal

whenever a train passes a given point, a code wheel, a reversible motor for driving the code wheel, and means responsive to the passage of a train for energizing the motor in opposite directions for opposite directions of the train movement.

18. In a signaling device, a code wheel, a motor for rotating said code wheel, a clutch between the motor and code wheel, means normally tending to retain said clutch into operative engagement, and means adapted to be electrically energized to move said clutch to disengage said motor from said code wheel.

19. In a system for transmitting a signal whenever a train passes a given point, a transmitter, and means for actuating the transmitter in opposite directions for opposite train movements, comprising a pair of controlling devices for the transmitter arranged to be operated in succession as the train passes the point, and means whereby the first device to be operated renders the other ineffective.

20. In a signaling system, an electric circuit, a plurality of transmitters arranged in parallel to the circuit, said circuit being open during non-signaling, and said transmitters when active being arranged to close and open the circuit intermittently, a source of motion for each transmitter, means whereby said source of motion is rendered active in response to the occurrence of an event associated with its transmitter, and means active only during the operation of any of the other transmitters for disconnecting the source of motion from its transmitter while maintaining the said source in motion.

21. In a signaling system, an electric circuit, a plurality of transmitters at spaced intervals along the circuit and arranged in parallel thereto, said circuit being open during non-signaling, and said transmitters when active being arranged to close and open the circuit intermittently, a source of energy near each end of the circuit, the sources being arranged in opposition, and means located near each transmitter for disabling it, said means being arranged in series relation in the circuit, whereby upon operation of any of the transmitters, the two sources of energy cause all of the disabling means associated with the other transmitters to operate.

In testimony whereof, I have hereunto set my hand.

FRANK A. MILLER.
